UNITED STATES PATENT OFFICE.

ADOLPH P. PALMER, OF OAKLAND, CALIFORNIA.

SEPARATOR AND AMALGAMATOR.

1,231,420.

Specification of Letters Patent. Patented June 26, 1917.

Application filed February 10, 1916. Serial No. 77,384.

To all whom it may concern:

Be it known that I, ADOLPH P. PALMER, a citizen of the United States, residing at Oakland, in the county of Alameda and 5 State of California, have invented new and useful Improvements in Separators and Amalgamators, of which the following is a specification.

This invention relates to an apparatus 10 which is especially designed for separating gold from sand or lighter material with which it may be mixed or associated.

It consists of a vertical main frame having a central, vertical shaft and a surrounding sleeve independently driven at different 15 rates of speed, one of said driven members carrying a cylindrical chamber, and the other carrying a pan revoluble within said chamber, the inner cylindrical sides of which 20 are grooved or channeled to carry a body of mercury, and a rotary member having openings through the lower portion and spiral flanges around the upper portion is carried so as to extend into the second cup- 25 shaped member. Interiorly of the revoluble members is a stationary chute with connections by which material to be treated is delivered into the inner pan; thence passing out through the perforated, spirally grooved 30 rotary member the material is thrown into contact with the mercury containing channel and thence continues to flow upwardly around and between the spiral channels which maintain it in contact with the mer- 35 cury lined cylinder, after which it discharges into the outer chamber of the frame and thence downwardly through openings in the bottom thereof.

It also comprises details of construction 40 which will be more fully explained by reference to the accompanying drawings, in which—

Figure 1 is a vertical section of the apparatus.

45 Fig. 2 is a horizontal cross-section on line 2—2 of Fig. 1.

Fig. 3 is a detail elevation of the revoluble table.

As shown, this apparatus consists of a 50 rigid frame A, which may be made of cast iron, or otherwise. Interiorly to this frame is a cylindrical-shaped receiver B, which may be fixed in place by means of a bearing or brace C and bolts 2 connecting it with the 55 exterior portion of the frame. From the upper part of this receiver B an annular

plate 3 extends inwardly, being bolted to the upper part of the receiver B, and its inner periphery carries a downwardly extending cylindrical chute 4, the lower end of which 60 is made open and convergent.

Centrally through this structure extends a shaft 5, turnable in bearings, as at 6. Surrounding this shaft and independently revoluble thereon is a sleeve 7 turnable in bearings 8 which surround the inner shaft. 9 is a cylindrical fastening, open at the upper end and having a segmental bowl-shaped bottom 9^a; and above this bottom and around the cylindrical portion of the chamber is a depression or groove 10 so that with centrifugal action any mercury in the bowl 9^a will be carried to the groove and, thus, all the mercury will be retained in a definite space while the machine is in operation. 70 This cylindrical chamber is secured to the inner shaft 5, below the end of the sleeve 8, and may be driven at a velocity of 2000 revolutions per minute.

Upon the lower end of the sleeve 7 is fixed 80 a pan or saucer-shaped table 11; the sleeve being revoluble at a rate of speed which may be proportionately 3000 revolutions per minute. 12 is a pulley, fixed to the upper part of the shaft 5 where it extends above the 85 sleeve 8, and 13 is a pulley fixed to the sleeve. Through these two power is transmitted to revolve the shaft and sleeve at different rates of speed.

Connected with the chute 4 are directing 90 troughs 14, through which pulp or material containing gold, mercury or other valuable material, which may be separated by gravity and by amalgamation, are delivered into the chute 4. From the bottom convergent end of 95 this chute the material drops into the revoluble table 11 and by centrifugal action is thrown outwardly through holes in a surrounding cylinder 15. This cylinder is secured to and carried by the pan exteriorly 100 to the chute 4 and above the perforations in the lower end, it has spiral flanges 16 which extend outwardly, and this device, located within the outer cylinder 9, forms an annular passage through which the material 105 thrown centrifugally through the holes in the member 15 will be caused to impinge against the mercury contained in the channel 10.

The centrifugal force and revolution of 110 the cylindrical member 9 causes any mercury which may be contained in the bowl

portion 9^a to move up into this channel and any surplus will be distributed along the inner face of the chamber which has a lip or flange at the top, as shown at 17, to arrest 5 any mercury, which may have arisen along the cylinder, from escaping. It also serves to retain any platinum which may be associated with the other material. The lighter less valuable portions which will not amalgamate will be carried up through the channel between the members 9 and 15 and the spiral flanges 16 will act to cause a spiral rotation and upward discharge of the pulp, which, passing out over the flange at the top 10 of the cylinder 9, will be delivered into the cylindrical receiver B from which it passes downward and outwardly through screened openings 18 at the bottom.

The inner shaft may be hollow, as shown 20 in dotted lines in Fig. 1, and have a cap, as at 19, at each end. Means are provided, as shown at 20, for the vertical adjustment of the shaft and the cylinder and pan.

When the revolution of the pan and bowl 25 stop the centrifugal flow of material will cease, and any mercury remaining in the channel 10 or the cylinder will gravitate into the bowl 9^a and will pass thence through holes 21 leading through the sides of the 30 shaft 5 to the interior.

Having thus described my invention, what I claim and desire to secure by Letters Patent is—

1. In an apparatus of the character described, a cylindrical chamber having a

bowl-shaped bottom and a continuous groove above the bottom and in the inner wall of the cylindrical portion whereby mercury in said bowl-shaped bottom may be delivered into the groove and be retained therein by 40 centrifugal action, and a rotary cylinder arranged within the chamber and provided at its bottom with a table and segmentally cut away to form an opening immediately above the table for permitting material to move 45 from the interior of the cylinder outwardly to the table for being delivered centrifugally therefrom to the mercury groove of the chamber, said table being spaced above the bowl-shaped bottom of the chamber. 50

2. In an apparatus of the character described, a cylindrical chamber, a revoluble dished table arranged within the chamber for delivering material centrifugally into the chamber, and a cylinder fixed at its lower end to the table and within the periphery of said table, said cylinder being segmentally cut away to form side openings immediately above said table for permitting material to move from within the cylinder 60 to the table and provided with a spiral conveyor flange above the openings thereof. 65

In testimony whereof I have hereunto set my hand in the presence of two subscribing witnesses.

ADOLPH P. PALMER.
